[57] CLAIM

The ornamental design for a watch housing, as shown and
described.

DESCRIPTION

FIG. 1 is a perspective view of a watch housing in accordance
with our invention;

FIG. 2 is a front view of the watch housing of FIG. 1;
FIG. 3 is a back view of the watch housing of FIG. 1;
FIG. 4 is a left side view of the watch housing of FIG. 1;
FIG. 5 is a right side view of the watch housing of FIG. 1;
FIG. 6 is a top view of the watch housing of FIG. 1; and,
FIG. 7 is a bottom view of the watch housing of FIG. 1.
The broken lines show the watch band for illustrative
purposes only and form no part of the claimed design.
